UNITED STATES PATENT OFFICE.

GEORGE J. NOPPER, OF BALTIMORE, MARYLAND.

CLOTH-CUTTER.

SPECIFICATION forming part of Letters Patent No. 686,529, dated November 12, 1901.

Application filed April 3, 1901. Serial No. 54,119. (No model.)

To all whom it may concern:

Be it known that I, GEORGE J. NOPPER, a citizen of the United States, residing at Baltimore, in the State of Maryland, have invented 5 certain new and useful Improvements in Cloth-Cutters, of which the following is a specification.

This invention relates to improvements in cloth-cutting machines of that class in which 10 the machine has a reciprocating knife actuated by electric motors and which is moved or shifted by the operator over the table supporting the layers of cloth to be cut so that the said knife will cut the layers of cloth 15 along the desired outlines.

The object of the invention is to provide a cloth-cutting machine of this character which will operate at a high rate of speed with little vibration, which will impart a direct vertical reciprocating motion to the cloth-cutting knife, and which will be balanced on the standard projecting upwardly from its base-plate, so that the machine may be easily and 20 accurately shifted by the operator over the table supporting the layers of cloth to be cut.

The invention consists in certain constructions, arrangements, and combinations of the parts hereinafter fully described and claimed, reference being had to the accompanying 25 drawings, in which—

Figure 1 is a front elevation of my improved cloth-cutting machine. Fig. 2 is a side elevation thereof. Fig. 3 is a top plan view of the machine. Fig. 4 is a vertical transverse 30 section taken approximately on the line 4-4 of Fig. 1. Fig. 5 is a side elevation of the lower portion of the machine as seen from the side opposite to that shown in Fig. 2. Fig. 6 is a horizontal sectional view taken 35 approximately on the line 6-6 of Fig. 4. Fig. 7 is a detail view illustrating the antifriction devices for the vertically-reciprocating cross-head which carries the knife-holder.

Referring to the drawings, the letter A designates a horizontal base-plate provided on 40 its under side with rollers *a*, by which it is supported to move over a cloth-supporting table, and also provided with a beveled edge *a'*, adapted to take under the layers of cloth, 45 so that the latter will ride up on the upper surface of said base-plate and come into con-

tact with the vertically-reciprocating cloth-cutting knife *b*. From the center of said base-plate A rises a vertical standard B, slotted, as at *b'*, at its front edge and which forms 55 a guide for the said cloth-cutting knife. A casing C is rigidly secured to the upper end of said standard and extends above the same in approximate vertical alinement therewith and is provided on each of two opposite sides 60 with a vertical guideway *c* and is also provided at its front with two forwardly-extending vertical spaced-apart guide-plates *c'*. Two horizontal bracket-arms D are rigidly secured to said casing, and each of said arms 65 projects laterally from one of those sides of the casing in which the guideways are located. An electric motor E is supported on the outer end of each bracket-arm, said two motors being of equal weight and equidistant 70 from said standard and casing, whereby the machine is accurately balanced, as best indicated in Figs. 1 and 3.

The axes *c* of the two motors E extend horizontally in alinement with each other and 75 are provided on each of their inner or adjacent ends with a crank *d*. The said cranks are balanced by segments *e*. A crank-pin *f* connects the two cranks, and by this arrangement the said two motor-axes are practically 80 converted into one main horizontal driving-shaft provided with a double crank whose pin *f* is located directly over the casing C and at the vertical center of the machine. Connected to said crank-pin *f* by a pitman-box *g* 85 is the upper end of a vertical pitman *h*, which extends down into the casing C and whose lower end is connected to the upper end of a vertically-reciprocating cross-head *i*. The said cross-head is provided at its upper and 90 lower ends with two pairs of oppositely-extending stub-shafts *i'*, on which are journaled antifriction-rollers *i''*, as shown in Fig. 7, mounted to move in the vertical guideways *c'* of the casing C, and a knife-holder *j* projects forwardly from said cross-head and is moved thereby up and down between the two spaced-apart guide-plates *c'* of said casing. In this instance the said knife-holder is an integral part of the cross-head; but it is manifest that it may be riveted or otherwise secured thereto.

One of the vertical guide-plates c^2 is provided on its inner side with a vertical recess k , and the adjacent side of the knife-holder j is also provided with a vertical recess k' , as shown in Fig. 3, and the cloth-cutting knife b fits in a slotted standard B and between the guide-plates c^3 and is provided with an upper forked or slotted end l , entering between the said two recesses k k' and rigidly but adjustably attached to the sliding knife-holder j by a clamping-screw m , whereby it will slide up and down with the said holder and may be adjusted vertically when desired with respect to the latter.

15 In order to keep the layers of cloth that are being cut by the vertically-reciprocating knife from being raised by the same during its rapid upward movements, I have provided a guard comprising a vertical longitudinally-slotted shank n , secured at any desired vertical adjustment to the outer side of one of the guide-plates c^2 by a clamping-screw o , and a toe p , which is rigidly attached to the lower end of said shank and projects forwardly alongside 25 of the knife b and curves upwardly beyond the front vertical edge of the latter, said toe being provided with a spur q , which extends laterally across the front edge of the knife and thence rearwardly, as shown best in Fig. 6. 30 The said guard is adjusted vertically above the upper surface of the base-plate A , according to the height or combined thickness of the layers of cloth intended to be cut and which lie upon said base-plate and pass under said guard as the machine is moved forwardly. 35 The guard prevents the cloth from being raised by the rapid upward movements of the knife.

The driving crank-shaft of the machine is 40 covered by a part-cylindrical hood r , which extends from one motor-casing to the other and prevents lint and dust from settling on the shaft and other adjacent interior parts. Said hood is provided at its top with an opening s , through which oil may be introduced 45 to the various working parts, and a plate t is detachably secured to the hood and normally covers said opening.

The machine may be guided over the 50 surface of the cloth-supporting table by a handle u , secured to the cover-plate t at the top of the machine, or by another handle v , secured to the rear of the machine, as shown best in Figs. 2 and 4.

55 In practice the operator starts the motors and grasps either of the handles u or v and moves the machine over the cutting-table on which the layers of cloth are supported, causing the latter to rise up on the base-plate A 60 and into contact with the knife b , which is vertically reciprocated by the horizontal crank-shaft, cross-head i , and pitman h . It is obvious that the crank-shaft may be rotated by either one of the electric motors instead 65 of both if it is desired to cut but a few layers of cloth.

It will be seen that the cloth-cutting machine hereinbefore described is provided with electric motors which accurately balance the machine, that the arrangement of horizontal crank-shaft with its central balanced double crank gives a direct vertical reciprocation to the knife at the center of the machine, thereby avoiding vibration and increasing the stability and durability of machine, and that the arrangement of cross-head i with its antifriction-rollers working in guideways in the casing C enables the machine to run smoothly and reduces friction of the working parts.

Having thus described my invention, what I claim as new, and desire to secure by Letters Patent, is—

1. A cloth-cutting machine comprising a base-plate; a vertical standard secured to said base-plate; a casing secured to said standard and extending above the latter and provided with two oppositely-extending bracket-arms; a motor secured on each bracket-arm, and provided with horizontal axes alined with each other; a double crank connecting the adjacent ends of said axes; a cross-head mounted in said casing and carrying a knife-holder; a pitman connected to said crank and also to said cross-head; and a cloth-cutting knife secured to said knife-holder and reciprocated thereby vertically in said standard.

2. A cloth-cutting machine, comprising a base-plate; a vertical slotted standard secured to said base-plate; a casing supported on said standard and extending above the same in vertical alinement therewith, and provided with two oppositely-vertical guideways and two forwardly-extending spaced-apart guide-plates; a horizontal driving-shaft mounted above said casing and provided with a crank directly above the latter; a vertically-reciprocating cross-head in said casing and having a pitman connection with said crank, said cross-head being provided with antifriction-rollers mounted on the cross-head and reciprocating up and down in said guideways, and said cross-head also provided with a forwardly-projecting knife-holder fitted between said guide-plates; and a cloth-cutting knife rigidly secured to said knife-holder and reciprocated thereby in said slotted standard, as set forth.

3. A cloth-cutting machine, comprising a base-plate; a vertical slotted standard secured to said base-plate; a vertical casing supported on said standard and extending above the same in vertical alinement therewith, and provided with two forwardly-extending vertical spaced-apart guide-plates; two oppositely-extending bracket-arms rigidly secured to said casing; a motor secured on each bracket-arm and said motors being equidistant from said casing and standard and provided with horizontal axes alined with each other; a double crank connecting the adjacent ends of said axes and located di-

rectly above said casing; a vertically-reciprocating cross-head in said casing and having a pitman connection with said double crank; a knife-holder rigid with said cross-head and fitted between said guide-plates; and a cloth-cutting knife rigidly secured to said knife-holder.

In testimony whereof I affix my signature in the presence of two witnesses.

GEORGE J. NOPPER.
